UNITED STATES PATENT OFFICE.

AARON E. ROSENTHAL, OF CHICAGO, ILLINOIS, ASSIGNOR TO CLARIN MFG. CO., OF CHICAGO, ILLINOIS, A CORPORATION OF ILLINOIS.

REMOVABLE FOOT FOR SUPPORTING LEGS.

Application filed November 13, 1925. Serial No. 68,813.

My invention relates to a removable foot for a supporting leg, and more particularly for the leg of a chair which is provided with tubular portions; and the main object of the invention is to provide a foot which comprises a smooth, resilient and non-abrasive floor engaging portion, and bent or curved resilient arms extending therefrom for engaging in said tubular portions of the chair leg to hold the foot in position thereon.

Other objects and advantages will become apparent from the following description taken in connection with the accompanying drawing, in which,

Fig. 1 is a side view of a chair with my improved foot mounted in position on the legs of said chair;

Fig. 2 is an enlarged view, partly broken away, showing the clamping or gripping engagement of the arms on said foot within the tubular portions of the chair leg;

Fig. 3 is a cross section on line 3—3 of Fig. 2; and

Fig. 4 is a vertical section through the foot.

The form of construction illustrated comprises a floor engaging portion or block 6, which is preferably constructed of rubber, or other suitable pliable or resilient and non-abrasive material, which will not injure the floors and will lend a slight amount of resiliency to the chair leg. Said block preferably also has the lower edges and corners rounded off or smoothed so as to prevent scratching or marring polished floors, rugs, etc.

A metallic member, which is preferably U-shaped or in the form of a bent rod, has its bight or intermediate portion 7 embedded within the block 6, and said member has arms or parts 8 and 9 extending upwardly from said block. Said rubber block is preferably moulded or formed upon said metallic member under pressure and heat, so as to be substantially integral therewith. Said metallic member is made of slightly resilient material, and preferably has one arm curved, as indicated at 9', and has the ends inclined and the entire arm arranged so as to enter the tubular portions 10 of the chair legs 11 and to firmly engage and clamp the walls in said tubular portions and hold the foot firmly but removably in position on said chair legs.

A suitable bearing member 12, preferably in the form of a metal washer, is placed on each arm 8 and 9 and is preferably embedded in the top of block 6, to prevent the bottom of the metal chair leg from cutting into the rubber or pliable material of the block 6 and from working its way down into said block.

This foot, as above disclosed, provides a particularly desirable and practical foot of this type of chair leg with tubular portions, and has combined the qualities of being inexpensive in construction, readily attachable to the chair leg or removable therefrom, and also provides resiliency to the chair leg and chair and entirely prevents marring or scratching of the floor, and as it is constructed of rubber it furthermore affords traction and gripping power and thereby prevents slipping of the chair on smooth and highly polished floors.

What I claim as my invention and desire to secure by Letters Patent is:

1. In combination with a supporting leg having tubular portions, a foot having a block of resilient material, a member having a part embedded in said block and having resilient arms extending therefrom and engaging in said tubular portions to clamp the foot in position thereon.

2. In combination with a supporting leg having tubular portions, a foot having a block of resilient material, a metallic member having a part embedded in said block and having arms extending therefrom to enter said tubular portions, one of said arms being curved and both of said arms being arranged to clamp the walls of said tubular portions and retain the foot in position thereon.

3. In combination with a supporting leg having tubular portions, a foot having a block of rubber material, a member of rigid material having a part embedded in said block and having arms extending therefrom into said tubular portions, said arms being bent and arranged to clamp the walls of said tubular portions, and a member on each arm and being embedded in the top of said block to prevent the edge of the leg from cutting into said block.

4. In combination with a supporting leg having tubular portions, a foot comprising a block of rubber material, a U-shaped metallic member having its bight embedded in

said block to be substantially integral therewith and having resilient arms extending upwardly therefrom to engage in said tubular portions, one of said arms having a 5 curved portion and said arm being inclined to firmly engage the walls of said tubular portions, and a washer on each arm and

being embedded in the top of said block to prevent the edge of the leg from cutting into said block.

In testimony whereof I have signed my name to this specification.

AARON E. ROSENTHAL.
